UNITED STATES PATENT OFFICE.

GEORGE P. WIGGINTON, OF KALAMAZOO, MICHIGAN, ASSIGNOR TO KALAMAZOO
LOOSE LEAF BINDER CO., OF KALAMAZOO, MICHIGAN.

TEMPORARY BINDER.

Application filed September 20, 1921. Serial No. 502,042.

To all whom it may concern:

Be it known that I, GEORGE P. WIGGINTON, a citizen of the United States, residing at the city and county of Kalamazoo, State 5 of Michigan, have invented certain new and useful Improvements in Temporary Binders, of which the following is a specification.

This invention relates to improvements in temporary binders.

10 The main objects of this invention are:

To provide an improved temporary binder which is well adapted for the holding of loose sheets, circulars and the like, is easily adjusted to secure the sheets and to permit 15 their removal or insertion and at the same time one in which the sheets are very securely held.

A further object is to provide an improved 20 binder having these advantages which is very neat and attractive in appearance and also economical to produce.

Further objects, and objects relating to structural details, will definitely appear from the detailed description to follow.

25 I accomplish the objects of my invention by the devices and means described in the following specification. The invention is clearly defined and pointed out in the claims.

30 A structure which is a preferred embodiment of my invention is clearly illustrated in the accompanying drawing, forming a part of this application, in which:

Fig. I is a rear perspective view of a temporary binder embodying the features of 35 my invention.

Fig. II is a detail section on a line corresponding to line 2—2 of Fig. I, a post being shown partially in full lines.

40 Fig. III is a detail section on a line corresponding to line 3—3 of Fig. II, the coupling members and posts being shown in full lines.

Fig. IV is a perspective view of one of 45 the post sections.

In the drawing similar reference characters refer to similar parts throughout the several views, and the sectional views are taken looking in the direction of the little 50 arrows at the ends of the section lines.

Referring to the drawing, the covers 1, 1 are, in the embodiment illustrated, connected by the flexible back 2. Within the covers are binding bars 3, the bars being 55 hinged to the covers by means of the flexi-

ble connections 4. These binding bars have holes 5 adapted to receive the studs 6 of the binding posts 7, the opposed bar having recesses 8 aligned with the holes, the recesses being adapted to receive the outer ends of 60 the posts, as shown in Fig. III.

The posts are preferably of the sectional type, as illustrated, and are provided with collar-like sheet-engaging heads 9 which engage the sheet body 10, the posts being arranged through the sheet body from opposite sides thereof, as shown in Fig. III. The sheet body is then secured together as a unit so that it may be removed as a unit from the binder or either cover may be opened, the 70 binding posts having their heads at the top removed and the sheets lifted from the opposed posts.

The binding bars are adjustably connected by the coupling members 11 formed of 75 adjustably connected sections 12 and 13, the section 12 being threaded into the section 13. The section 13 is pivoted at 14 to one of the binder bars while the section 12 has a head 15 adapted to detachably engage a slot 80 16 in the other bar, so that the coupling members may be engaged and disengaged with a swinging movement. The coupling members and the sectional posts may be readily adjusted to accommodate the sheet 85 body.

My improved binder is attractive in appearance and at the same time is very economical to produce and, while the sheets are effectively bound, they are very easily removed and replaced as occasion may require. 90

Having thus described my invention, what I claim as new, and desire to secure by Letters Patent is:

1. In a temporary binder, the combination with sheets provided with holes adapted to receive posts, of covers connected by a flexible back, binding bars hinged within said covers, sectional posts provided with collar-like sheet-engaging heads and with studs detachably engaging said binding bars, a part of said posts being arranged to enter from each side into the sheet body, the binding bars having recesses adapted to receive 100 the outer ends of the posts, and disengageable and extensible coupling members for said binding bars disposed at the ends thereof. 110

2. In a temporary binder, the combination with sheets provided with holes adapt-

- ed to receive posts, of covers connected by a flexible back, binding bars hinged within said covers, sectional posts provided with collar - like sheet - engaging heads and with 5 studs detachably engaging said binding bars, said posts being arranged to enter from each side into the sheet body, and disengageable and extensible coupling members for said binding bars disposed at the ends thereof
- 10 3. In a temporary binder, the combination of covers, binding bars hinged to said covers, posts provided with collar-like sheet-engaging heads and with studs detachably engaging said binding bars, the binding bars
- 15 having recesses adapted to receive the outer ends of the posts, and coupling members for said binding bars disposed at the ends thereof.
4. In a temporary binder, the combination of covers, binding bars hinged to said 20 covers, posts provided with collar - like sheet - engaging heads and with studs detachably engaging said binding bars, and coupling members for said binding bars disposed at the ends thereof. 25

In witness whereof I have hereunto set my hand and seal in the presence of two witnesses.

GEORGE P. WIGGINGTON. [L. s.]
